UNITED STATES PATENT OFFICE.

GUSTAV TRESENREUTER, OF BERLIN, GERMANY.

INCANDESCENT GAS-LAMP.

SPECIFICATION forming part of Letters Patent No. 707,185, dated August 19, 1902.

Application filed December 6, 1900. Serial No. 38,957. (No model.)

To all whom it may concern:

Be it known that I, GUSTAV TRESENREUTER, engineer, a subject of the Emperor of Germany, and a resident of 28 Schönhauser 5 Allee, Berlin, in the Province of Brandenburg, Germany, have invented certain new and useful Improvements in and in Connection with Incandescent Gas-Lamps; and I do hereby declare the following to be a full, 10 clear, and exact description of the invention, such as will enable others skilled in the art to which it appertains to make and use the same, reference being had to the accompanying drawings, and to letters of reference 15 marked thereon, which form a part of this specification.

My invention relates to incandescent gas-lamps which have the appearance when in use of burning with inverted flames. In a 20 lamp of this kind according to this invention the gas-supply pipe passes through the interior of the chimney, and thereby effects a very considerable heating of the gas. The lamp has preferably no cock; but when it is 25 unscrewed from the piping the said piping is automatically closed, so that an accidental escape of gas is impossible.

Figure 1 of the accompanying drawings is a 30 sectional elevation of an example of a lamp according to this invention. Fig. 2 is a plan of a guide-ring for the chimney.

A union *a*, with left-hand and right-hand threads, is screwed to ordinary gas-piping and to a gas-supply pipe *b* of small diameter, 35 from which extend downwardly two branches *c* and *d*, that lead to an air-tight chamber *e*, above which is a burner-support *f*, provided with openings *g* for the air-supply. The burner-support *f* carries at its upper end a 40 burner *i*, which is insulated by means of an asbestos ring *h* and over which a mantle *k* is suspended from a hook *l*. The burner-support *f* has a gallery *o*, which is provided with 45 openings *m* and is adapted to carry a chimney *p*, on the upper end of which a guide-ring *q* is mounted for the purpose of keeping the chimney coaxial with the burner. The upper end of the gas-supply pipe *b* terminates in an externally-screwed enlarged portion, in 50 the interior of which an abutment *s* of suitable size is arranged, so that when the pipe *b* is screwed into the union *a* it raises a ball

t, and thus allows the gas to pass through. An opening *v* in a plate *w* can be opened or closed by means of a small screw *u*, arranged 55 at the lower end of the lamp. Finally an opening *x* is formed somewhat above the burner on one of the two branches *c* *d* of the gas-supply pipe.

The mode of operation of the lamp is as follows: When the lamp is screwed to the gas-piping, the abutment *s* raises the ball *t* in the union *a*. The gas can then pass freely into the pipe *b* and thence to the branches *c* and *d*, through which it reaches the closed chamber *e*. Then when the small screw *u* has been unscrewed until the opening *v* in the plate *w* is uncovered the gas passes upward through the opening *v* and flows mixed with air to the burner *i*. The flame is ignited in the usual 60 manner above the chimney and ignites in turn at the opening *x* a pilot-flame, which then burns constantly. When the small screw *u* is screwed up, the gas can no longer pass through the opening *v*, and the flame is consequently extinguished; but as there is still 65 gas in the branches *c* and *d* the pilot-flame remains alight, so that the lamp can be lighted without the aid of any external igniting-flame 70 simply by unscrewing the small screw *u*. Since, as will be seen, the gas-supply pipe is arranged in this lamp in the interior of the chimney, the gas is considerably heated and 75 the efficiency is very much increased. The heat generated is so great that it is necessary 80 to insulate the burner by means of a ring of suitable material, as asbestos. When the lamp is disconnected—for example, for the purpose of changing the mantle or the glass chimney—the gas is automatically cut off, 85 since the ball *t* in the union *a* simply falls as soon as the abutment *s* is unscrewed with the gas-supply pipe *b*. Instead of two 90 branches *c* and *d* the pipe *b* may have only one branch or more than two branches. 95

Having thus described my invention, what I claim as new therein, and desire to secure by Letters Patent of the United States of America, is—

1. In a gas-lamp, a burner, a mantle suspended over the same, a chimney and one or more gas-feed pipes between the chimney and the mantle, substantially as set forth. 100
2. In a gas-lamp, a burner, a mantle sus-

pended over the same, a chimney, a burner-support forming a mixing-chamber and provided with air-inlets, an air-tight chamber forming part thereof and gas-pipes proximate to the exterior of the mantle, passing through the chimney and the mixing-chamber to the air-tight chamber, means for admitting gas from the air-tight chamber to the mixing-chamber and a pilot-flame burner proximate to the exterior of the mantle fed by one of said pipes, substantially as set forth.

3. In a gas-lamp, a mixing-chamber, a burner connected therewith and an incandescent mantle surrounding the burner, a bifurcated gas-feed pipe whose branches are in communication with said mixing-chamber, one of said branches provided with a jet-orifice proximate to the mantle, and means for arbitrarily controlling the supply of gas to the mixing-chamber; in combination with a chimney surrounding the burner and feed-pipe, for the purpose set forth.

4. A gas-lamp comprising a mixing-chamber, a burner connected therewith, an incandescent mantle surrounding the burner and a bifurcated gas-feed pipe in communication with said mixing-chamber and having an extension between its branches provided with a hook for supporting the aforesaid mantle, for the purpose set forth.

5. In a gas-lamp, a mixing-chamber, a burner connected therewith, an incandescent mantle surrounding said burner, a bifurcated

gas-feed pipe whose branches are in communication with said mixing-chamber, an extension from said pipe between its branches and a hook screwed into said extension for supporting the incandescent mantle; in combination with a chimney surrounding the mantle and feed-pipe, for the purpose set forth. 35

6. In a gas-lamp, a burner, a mantle suspended over the same, a chimney, gas-feed pipes in the form of a rectangle between the chimney and mantle, and a jet-orifice in one of said pipes proximate the lower portion of 45 the mantle, substantially as set forth.

7. In a gas-lamp, a burner, a mantle suspended over the same, a burner-support of insulating material, a mixing-chamber forming part of the support and provided with air-inlets, a gas-chamber below and forming part of the mixing-chamber, a chimney, gas-pipes proximate the exterior of the mantle passing through the chimney and the mixing-chamber to the gas-chamber, one of said pipes provided with a pilot-flame orifice and a needle-valve to control the exit of gas from the gas-chamber to the mixing-chamber and burner, substantially as set forth. 50 55

In testimony that I claim the foregoing as 60 my invention I have signed my name in presence of two subscribing witnesses.

GUSTAV TRESENREUTER.
